Primary Examiner — Melanie Pellegrini(57) **CLAIM**

The ornamental design for an electrocardiographic device, as shown and described.

DESCRIPTION

1. Electrocardiographic device

1.1 : Perspective

1.2 : Front

1.3 : Back

1.4 : Left

1.5 : Right

1.6 : Top

1.7 : Bottom

1.8 : Perspective

Fig. 1.1 is a top front perspective view of an electrocardiographic device showing our new design; fig. 1.2 is a front view thereof; fig. 1.3 is a rear view thereof; fig. 1.4 is a left side view thereof; fig. 1.5 is a right side view thereof; fig. 1.6 is a top view thereof; fig. 1.7 is a bottom view thereof; and, fig. 1.8 is a bottom front perspective view thereof; the dashed broken lines in the figures show portions of the

(Continued)

electrocardiographic device that form no part of the claimed design; the shade lines in the figures show contour and not surface ornamentation.
